UNITED STATES PATENT OFFICE.

GEORGE E. FISHER, OF CLEVELAND, OHIO.

FUSE-CARTRIDGE.

1,147,494.

Specification of Letters Patent. Patented July 20, 1915.

Application filed June 22, 1914. Serial No. 846,550.

To all whom it may concern:

Be it known that I, GEORGE E. FISHER, citizen of the United States, residing at Cleveland, in the county of Cuyahoga and 5 State of Ohio, have invented certain new and useful Improvements in Fuse-Cartridges, of which the following is a specification.

This invention relates to fuses, and particularly to that class known as fuse cartridges, which can be readily renewed or inserted in position when desired for use.

It comprises a fusible wire or other member located in a casing and connected to 15 contact terminals at the ends of the casing in a new and improved manner.

The invention is illustrated in the accompanying drawing, in which;

Figure 1 is a side elevation partly in section, of the fuse. Fig. 2 is a partial side elevation in longitudinal section. Fig. 3 is a detail of the end of the holder.

Referring specifically to the drawings, 4 indicates a hollow tubular holder or casing 25 preferably made of fiber. Within this is a fusible wire 7, and the tubular holder is filled with powdered or porous insulating material indicated at 9, which surrounds the fuse wire. This wire is hooked at its ends 30 as indicated at 7^a to engage over hanger plates 6 which are notched as at 6^a where the hooks engage. These plates are mounted in the ends of the tube, the ends of the plates fitting in slots 4^a in the tube. The 35 ends of the tube are closed by metal caps 5 fitting thereover and around the ends of the plates 6, and these caps are provided with contact points or rivets 5^b which fasten to the caps the ends of contact plates 5^a fitting 40 within the tube beside the wire 7. The caps are fastened on the tube by screws 8 which extend through the flanges of the cap and through the tube, and press at their inner ends against the plates 5^a, holding them in

close contact with the wire 7. The screws 45 thus serve the double purpose of fastening the caps in position and holding the plates in contact with the wire.

The fuse wire may be renewed at any time by taking off the caps, pulling out the 50 fuse wire and putting a new wire in place, bending the ends thereof over the holding plates 6, and the other parts of the cartridge do not have to be thrown away.

What I claim as new is:—

1. A fuse comprising a tubular casing with slots at the ends, cross pieces resting in said slots, a wire extending in the casing between said cross pieces, the ends of the wire being in supporting engagement with 60 said cross pieces, and caps on the opposite ends of the casing provided with contact devices bearing against the wire.

2. A fuse comprising a tube having slots extending inwardly from its ends, cross 65 pieces fitting in said slots and extending across the tube, a wire in the tube having its ends hooked over said cross pieces, caps on the ends of the casing, covering said slots and covering the ends of the cross pieces to 70 hold the latter in the slots, and conducting connections to said wire.

3. A fuse comprising a tubular casing, cross pieces at the ends of said casing, a fusible member supported within the tube by 75 said cross pieces, removable caps on the ends of the tube, a contact plate projecting from each cap against said member, and a fastening screw extending through the cap and tube and bearing against the plate to hold 80 the same against said member.

In testimony whereof, I affix my signature in presence of two witnesses.

GEORGE E. FISHER.

Witnesses:
